DESIGN FOR A GAME BOARD

Donald G. Campbell and Douglas R. Wiser,
Los Angeles, Calif.

Application November 10, 1934, Serial No. 53,964

Term of patent 3½ years

To all whom it may concern:

Be it known that we, Donald G. Campbell and Douglas R. Wiser, citizens of Canada and the United States, respectively, residing at Los Angeles, in the county of Los Angeles and State of California, have invented a new, original, and ornamental Design for Game Board, of which the following is a specification, reference being had to the accompanying drawing, forming part thereof.

The figure is an isometric view of a game board showing our design.

We claim:

The ornamental design for a game board as shown.

DOUGLAS R. WISER.
D. G. CAMPBELL.
